UNITED STATES PATENT OFFICE.

FRANK KUHN, OF DETROIT, MICHIGAN.

STORAGE-RACK.

1,119,837.

Specification of Letters Patent.

Patented Dec. 8, 1914.

Application filed May 31, 1912. Serial No. 700,793.

To all whom it may concern:

- Be it known that I, FRANK KUHN, a citizen of the United States of America, residing at Detroit, in the county of Wayne and 5 State of Michigan, have invented certain new and useful Improvements in Storage-Racks, of which the following is a specification, reference being had therein to the accompanying drawings.
- 10 The invention relates to storage racks designed for use in warehouses, stock rooms and other places where it is desirable to store articles as compactly as possible and so as to be accessible.
- 15 It is the object of the invention to obtain a fire-proof construction which may be manufactured at small cost from standard metal bars, and which possesses strength and rigidity, and can be adapted to receive any 20 size of box or storage receptacles.

In the drawings: Figure 1 is a perspective view of a portion of the storage rack. Fig. 2 is a horizontal section thereof. Fig. 3 is a vertical section. Fig. 4 is an enlarged section showing one of the joints.

The structural elements which I employ for forming my improved construction of storage rack are angle bars of standard form and size. These bars are punched, slotted 30 and bent to form the various members, the detail construction being as follows: A are vertical bars or stanchion members, which are properly spaced from each other by horizontally extending bars B arranged at intervals. Both bars A and B are angles and the bars B have their horizontal flanges provided with V-shaped notches C adapted to receive the bars A with their flanges arranged at substantially a 45 degree angle to 35 the plane of the bars B. The bars A and B are then secured to each other by bolts D passing through the angles and the vertical flange of the bar B and secured by a clamping nut E. The two sides of the rack are 40 thus formed by bars A and B secured as described and parallel with each other. These two frames are then cross connected by horizontal bars E, which also form supports and slide-ways for the individual boxes or receptacles in which the articles are stored. The bars E are also angles and to permit of attachment to the angularly arranged bars A the flanges E' are slotted at E² so as to 45 permit the vertical flanges E³ to be bent into conformity with the flange of the bar A. These bent portions are then secured by

bolts F in passing through punched or drilled registering apertures in the adjacent flanges. If desired at one end of the bars E the slitting may be parallel with the vertical flange as shown at E⁴ so as to leave a longer flange E', the end E⁵ of which is turned up to form a stop limiting the movement of the box or receptacle.

The bars B may be reinforced by oppositely arranged truss bars G placed with their vertical flanges abutting against those of the bars B and secured thereto by the bolts D. The frame is further strengthened by diagonal truss bars G arranged at suitable intervals and connecting the opposite bars A as shown.

The structure as described can be readily manufactured in any shop provided with a punch-press or drill-press and may be made to accommodate any space available. When completely erected suitable receptacles are provided of a size to fit between the vertical bars or stanchions A and of a height to occupy the space between the successive cross bars E. These receptacles are accessible from either one or both sides of the rack and may be slid out on the horizontal flanges E'. All of the parts being formed of metal the structure is obviously fire-proof.

What I claim as my invention is:

1. A storage rack comprising parallel, vertical angle bars spaced from each other with their apices extending oppositely, angle cross bars connecting said vertical bars, having their horizontal flanges slit and their vertical flanges bent to conform to the angle of the flanges of said vertical bars.

2. A storage rack comprising parallel vertical angle bars having their apices extending oppositely, horizontally extending angle bars connecting said vertical bars, their horizontal flanges being slotted to permit the vertical flanges to be bent into conformity to the angle of said vertical bars, and bolts for securing said horizontal and said vertical bars.

3. A storage rack comprising a series of pairs of parallel vertical angle bars with their apices extending oppositely, horizontal angle bars arranged in the planes of the bars on opposite sides of the bars and notched to form seats for said vertical bars, bolts for connecting said horizontal and said vertical bars passing through the apices of the latter and horizontal cross bars between the members of the bars having their horizontal

- flanges slitted to permit the vertical flanges being bent into parallelism with the flanges of said vertical bars, and bolts for securing said bent flanges to said vertical bars.
5. A storage rack comprising a series of pairs of parallel vertical angle bars having their apices extending oppositely, horizontal angle bars having notched flanges forming seats for said vertical bars, bolts passing 10 through the apices of said vertical bars and the vertical flanges of said horizontal bars, and diagonal truss rods extending between the opposite vertical bars of a pair, and having their ends passing through the apices of 15 said bars and adjacent flanges of the horizontal bars.
5. A storage rack comprising pairs of parallel vertical angle bars having their apices extending oppositely, horizontal bars connecting the corresponding members of said 20 pairs of vertical bars, horizontal cross bars connecting the members of the same pair of vertical bars, the horizontal flanges of said cross bars being slitted and the vertical flanges being bent at the slit to lie adjacent 25 to the flanges of said vertical bars.

In testimony whereof I affix my signature in presence of two witnesses.

FRANK KUHN.
